UNITED STATES PATENT OFFICE.

PETER FANDEL, OF GIBSON, LOUISIANA.

MEANS FOR OPERATING CHANGEABLE EXHIBITORS.

1,227,409.

Specification of Letters Patent.

Patented May 22, 1917.

Application filed September 15, 1916. Serial No. 120,398.

To all whom it may concern:

Be it known that I, PETER FANDEL, a citizen of the United States, residing at Gibson, in the parish of Terrebonne and State 5 of Louisiana, have invented new and useful Improvements in Means for Operating Changeable Exhibitors, of which the following is a specification.

This invention relates to improvements in 10 means for operating changeable exhibitors and has particular application to a station indicator for use on street cars, interurban cars, and railway trains.

In carrying out the present invention, it is 15 my purpose to provide a station indicator which will be found especially useful on trolley cars, and which will operate automatically after passing each station to indicate to the passengers the name of the next 20 station or stop, and wherein the driving connections will be connected with the trolley pole in such manner that when the position of the trolley pole is reversed incident to the car reaching the terminus of the line, and 25 starting back over the line, the driving connections will be reversed so that the sign belt will travel in the opposite direction.

It is also my purpose to provide a station 30 indicator wherein the sign belt will be automatically advanced in a step by step manner as the car passes from one station to another and wherein an improved construction is employed for effecting this result.

A further object of my invention is the 35 provision of operating mechanism for a changeable exhibitor which will be constructed in such manner that the exhibitor may be driven in one direction or the other, and wherein the component parts will be 40 so arranged and correlated as to reduce the possibility of derangement to a minimum.

With the above and other objects in view, the invention consists in the construction, combination, and arrangement of parts 45 hereinafter set forth and falling within the scope of the claims.

In the accompanying drawings:—

Figure 1 is a fragmentary longitudinal sectional view through a car equipped with 50 a station indicator and operating mechanism therefor constructed in accordance with the present invention.

Fig. 2 is a cross sectional view through the drive shaft, showing the operating 55 mechanism in side elevation.

Fig. 3 is a sectional view on the line 3—3 of Fig. 2.

Fig. 4 is a similar view on the line 4—4 of Fig. 2.

Referring now to the drawings, 1 designates a horizontal drive shaft journaled in suitable bearings carried by the end bars of one of the trucks of the car. Fixed upon the drive shaft 1 is a ratchet wheel 2, while loosely surrounding the drive shaft 1 at 60 one side of the ratchet wheel 2 is a hub 3, and radiating from the hub 3 are arms 4 spaced apart equal distances around the hub. Connected to the outer ends of the respective arms 4 and disposed at right angles thereto are pivot pins 5 overlying the ratchet wheel, and pivoted upon the respective pins 5 are pawls 6 adapted to engage the ratchet wheel. In the present instance, the pawls are arranged in two pairs, and the 65 pawls in one pair are disposed reversely to those in the other pair so that the ratchet wheel may be rotated in either direction according to the arrangement of the pawls 70 engaging the wheel. Also carried upon the outer end of each arm 4 is a cup 7 carrying a spring 8 that engages the pawls and acts to hold the latter in engagement with the ratchet wheel. Loosely mounted upon the 75 shaft 1 at the other side of the ratchet wheel 80 is a hub 9 from which radiate arms 10—10 and connected to the outer ends of the arms 10—10 are cam shoes 12, respectively, disposed concentrically of the ratchet wheel 85 and movable into engagement with either 90 pair of pawls to swing the latter out of engagement with the ratchet wheel so that the ratchet wheel will be relieved of the influence of such pawls in order that the other 95 pawls may rotate the wheel. One of the arms 4 is relatively long and has the lower end thereof equipped with a weighted shoe 13 adapted to strike an obstacle 14 in the travel of the car, so that the arms 4 may be rotated about the shaft 1 to rotate the 100 ratchet wheel. The obstacles 14 are arranged in advance of the respective stations along the line of travel of the car so that the ratchet wheel and shaft will be rotated as the car approaches the station.

Also radiating from the hub 9 are arms 105 15—15 and connected to the outer ends of the arms 15—15 are the lower extremities of cables 16, respectively, trained over suitably arranged guide wheels 17 carried by 110

the car and the upper ends of the cable 16 are connected with a collar 18 that surrounds the trolley pole of the car and is fixed to such pole, as clearly shown in Fig. 1 of the drawings. The guide rollers on one cable are so arranged relatively to those on the other cable that when the trolley pole is moved to one end of the car the pull will be exerted upon one of the cables, and the other cable permitted to become slack and vice versa. In this movement of the cables, the pulling cable acts to swing the arms 15 and the arms 10 around the shaft 1 so as to bring the shoes 12 into engagement with one pair of the pawls 6, so that the ratchet wheel will be relieved of the influence of such pawls. When the cam shoes swing one pair of the pawls out of engagement with the ratchet wheel the remaining pawls are permitted to engage the ratchet wheel so that the latter may be rotated in the proper direction. For instance, as shown in Fig. 2 of the drawings, the active pawls will rotate the ratchet wheel and the shaft counter-clockwise when the weighted shoe 13 rides over the obstacle 14, and as soon as the shoe disengages the obstacle the pawls will be restored to normal position under the weight of the shoe so as to obtain a fresh grip upon the ratchet wheel to again turn the latter when the weighted shoe rides over other obstacles. On the other hand, should the inactive pawls be relieved of the shoes 12 and the active pawls rendered inactive by such shoes, the wheel engaging pawls will idle over the ratchet wheel when the weighted shoe rides over the obstacle and rotate the ratchet wheel in a clockwise direction upon the weighted shoe disengaging the obstacle and returning to normal position under its weight, thereby revolving the ratchet wheel and shaft in the reverse direction.

The indicating device comprises a substantially rectangular casing 19 adapted to be mounted in the car within the vision of the passengers. The front wall of the casing 19 is formed with a window 20, while journaled in the side walls of the casing and extending across the latter adjacent to the lower and upper ends thereof are drive shafts 21 and 22, respectively designed to carry winding drums for the indicator belt. The indicator is shown conventionally in Fig. 1 and is driven by chain 39 from sprocket wheel 37 fixed on shaft 38 and the shaft last-named is driven from the shaft 1 through the medium of chain 41.

From the foregoing description taken in connection with the accompanying drawings, the construction and mode of operation of my improved sign exhibitor will be readily apparent. It will be seen that when the shaft 1 is rotated in one direction or the other dependent upon which pair of pawls

transmitted through the chain 41, the shaft 37, and the chain 39 to the indicator. Thus the indicator will be actuated in a step by step manner as the car passes from one station to another to advise the passengers of the name of the station that the car is approaching.

While I have herein shown and described the preferred form of my invention by way of illustration, I wish it to be understood that I do not limit or confine myself to the precise details of construction herein described and delineated as modification and variation may be made within the scope of the claims and without departing from the spirit of the invention.

I claim:—

1. Operating mechanism for changeable exhibitors comprising a shaft, driving mechanism between said shaft and the exhibitor whereby the latter may be actuated from the shaft, a ratchet wheel fixed upon said shaft, arms radiating from the shaft at one side of the ratchet wheel thereon and loosely mounted upon the shaft, reversely disposed pawls on the outer ends of the said arms, respectively, adapted to engage said ratchet wheel, means movable between the ratchet wheel and each of the pawls to relieve the ratchet wheel of the influence of such pawl, whereby the ratchet wheel may be rotated in one direction under the action of the other pawl, and means for revolving said arms around the shaft to actuate the ratchet wheel.

2. Operating mechanism for changeable exhibitors comprising a shaft mounted for rotary movement, driving mechanism between said shaft and the exhibitor, a ratchet wheel fixed upon said shaft, arms loosely mounted upon said shaft and radiating therefrom, reversely disposed pawls on the outer ends of the said arms adapted to engage the ratchet wheel, cam shoes each movable between the ratchet wheel and a given pawl, whereby the remaining pawl may engage the ratchet wheel to turn the latter in one direction, and means for actuating said arms to impart rotary movement to said ratchet wheel.

3. Operating mechanism for changeable exhibitors comprising a shaft mounted for rotary movement, driving mechanism between said shaft and the exhibitor, a ratchet wheel fixed upon said shaft, arms loosely mounted upon said shaft and radiating therefrom, reversely disposed pawls on the outer ends of the said arms adapted to engage the ratchet wheel, cam shoes each movable between the ratchet wheel and a given pawl, whereby the remaining pawls may engage the ratchet wheel to turn the latter in one direction, means for swinging said arms in one direction to rotate the ratchet wheel, and a weight for restoring said arms to normal position.

4. Operating mechanism for changeable exhibitors comprising a shaft mounted for rotary movement, driving mechanism between said shaft and the exhibitor, a ratchet wheel fixed upon said shaft, arms loosely mounted upon said shaft and radiating therefrom, reversely disposed pawls on the outer ends of the said arms adapted to engage the ratchet wheel, cam shoes each movable between the ratchet wheel and a given pawl, whereby the remaining pawls may engage the ratchet wheel to turn the latter in one direction, means for actuating said arms to impart rotary movement to said ratchet wheel, and arms rotatably mounted upon said shaft and radiating therefrom and carrying said cam shoes.
5. Operating mechanism for changeable exhibitors comprising a shaft mounted for rotary movement, driving mechanism between said shaft and the exhibitor, a ratchet wheel fixed upon said shaft, arms loosely mounted upon said shaft and radiating therefrom, reversely disposed pawls on the outer ends of the said arms adapted to engage the ratchet wheel, cam shoes each movable between the ratchet wheel and a given pawl, whereby the remaining pawls may engage the ratchet wheel to turn the latter in one direction, means for actuating said arms to impart rotary movement to said ratchet wheel, arms rotatably mounted upon

said shaft and radiating said cam shoes to said arms to swing said shaft to engage the cam of pawls and engage the other set.

6. Operating mechanism for changeable exhibitors comprising a shaft mounted for rotary movement, driving mechanism between said shaft and the exhibitor, a ratchet wheel fixed upon said shaft, arms radiating from said shaft at one side of the ratchet wheel and loosely mounted upon the shaft, reversely disposed pawls on the outer end of the said arms, respectively, adapted to engage said ratchet wheel, shoes, each movable between the ratchet wheel and a given pawl to relieve the ratchet wheel of the influence of such pawl, whereby the ratchet wheel may be rotated in one direction under the action of the other pawl, means for revolving said arms around the shaft to actuate the ratchet wheel, and means controlled by the movements of the trolley pole to reverse the positions of said shoes so that the said shaft may be rotated in one direction or the other according to the direction of travel of the car. 55

In testimony whereof I affix my signature.

PETER FANDEL.
